STERILIZER

Alfred Vischer, Jr., Park Ridge, Ill., assignor, by mesne assignments, of twelve thirtieths, to Alfred Vischer, Jr., two thirtieths to William Vischer, two thirtieths to Alfred Vischer, III, two thirtieths to Alfred Vischer, Jr., as trustee, four thirtieths to Walter W. Zitzewitz, four thirtieths to Elmer K. Zitzewitz, one thirtieth to Gertrude J. Zitzewitz, one thirtieth to Barbara O. Zitzewitz, and two thirtieths to Gertrude V. Bouton

Application January 25, 1943, Serial No. 473,471

6 Claims. (Cl. 21—56)

1

My invention pertains to sterilizers and more particularly to a sterilizer adapted to be operated by electricity supplied from the lighting circuit of a house, office building, or other suitable source of supply.

There are now on the market various sterilizers intended to be used in doctors' offices, dentists' offices, bacteriological and similar laboratories and in other like establishments. Most of these sterilizers, however, are heavy, expensive, wasteful of current, or difficult to operate, and there is an increasing demand for a light, inexpensive, automatic, electrical sterilizer which requires a minimum of current and which can easily be operated by a person with no special training. This demand has been made more acute by the need for such a sterilizer in military field hospitals, on ship board and for similar uses. An object of my invention is to provide such a sterilizer.

Another object of my invention is to provide a sterilizer having a new and improved sealing means for preventing the escape of steam from the compartment containing the articles to be sterilized.

Another object of my invention is to provide a sterilizer having new and improved means whereby the period of operation is automatically controlled and may be pre-set for widely different periods of operation to adapt the sterilizer for widely different conditions of use.

Another object of my invention is to provide a sterilizer which is entirely safe even in unskilled hands.

Other objects and advantages will become apparent as the description proceeds.

In the drawings:

Fig. 1 is a vertical sectional view taken through the container in which the articles to be sterilized are placed;

Fig. 2 is a partial horizontal section taken on the line 2—2 of Fig. 1 and showing the manner in which the door is held in sealed position;

Fig. 3 is an end view of the container and shows the door in closed position;

Fig. 4 is a view similar to Fig. 2, but showing the door before it is brought into sealing engagement with the container;

Fig. 5 is a vertical sectional view of the door controlling mechanism and is taken on the line 5—5 of Fig. 4;

Fig. 6 is a transverse sectional view of the door controlling mechanism and is taken on the line 6—6 of Fig. 5;

Fig. 7 is a perspective view of the switch control mechanism and shows a manual control for

2

pre-selecting the operating period of the sterilizer; Fig. 8 is a top view of the switch control mechanism with the cover removed;

Fig. 9 is a partial, vertical, longitudinal section through the switch control housing and illustrating the mercury switches in one position;

Fig. 10 is a partial, vertical, transverse section of the switch control mechanism taken on the line 10—10 of Fig. 9;

Fig. 11 is a view generally similar to Fig. 10, but taken on the line 11—11 of Fig. 9;

Fig. 12 is a wiring diagram showing the heating elements, control switches therefor and the electrical connections for the heating elements and control switches;

Fig. 13 is a view similar to Fig. 2, but showing a modified form of my invention; and

Fig. 14 is an end view of the embodiment of Fig. 13 and showing part of the handle broken away.

Referring to Fig. 1, it will be seen that I have illustrated therein an embodiment of my invention which comprises a container 20, inexpensively formed of sheet metal or other suitable material, and mounted on a pair of legs 22 and 24. In the particular embodiment illustrated, the legs 22 and 24 are attached to bands 26 and 28, respectively, which surround the container 20 at spaced intervals and are welded or otherwise suitably secured thereto in any convenient manner. The container 20 is provided with an opening 30 through which the articles to be sterilized may be inserted and removed and also through which water may be supplied to the interior of the container for purposes hereinafter described. This opening 30 is adapted to be closed by a door 32.

The interior of the container is preferably provided with shelves for supporting the articles to be sterilized. In Fig. 1 I have illustrated my container as having three shelves 34, 36 and 38, although it will be understood that the number and spacing of the shelves may be varied to suit the particular use to which the sterilizer is to be put. Each shelf is illustrated as comprising angle irons 40 of sheet metal or other suitable material welded or otherwise attached to the walls of the container 20 and a wire-mesh 42 extending between the angle irons 40 and serving as a support for the articles located on the shelf. In lieu of the wire mesh 42, any other suitable material may be used and while it is desirable to make the shelves of perforated or foraminous material, these shelves may be made of impervious material arranged to provide access for the steam to the articles located on the shelves.

The means for closing the opening 30 which I have provided is particularly simple and effective and can be readily operated by a person with no special training. This closure means is so designed that it may be readily closed and sealed after the articles to be sterilized have been placed on the shelves and this closure means may be as quickly unsealed and removed to permit removal of these articles after sterilization.

The door 32 is preferably made of stainless steel sheet 44, or other suitable resilient material supported in a ferrule 46 attached to a rod 48 supported in a sleeve 50. The sleeve 50 has a rectangular neck 52 loosely fitting in a rectangular opening 54 in a door supporting strap 56 pivoted at 58 to a side of the container 20. The strap 56 is made of such length that its free end 60 engages the opposite wall of the container when the door is in closed position, as shown in Fig. 2.

The sleeve 50 is held by its rectangular neck against rotation in the door supporting strap 56 and a key 62 fixed in the member 50 extends into a slot 63 in rod 48, whereby this rod is held against rotation but is permitted to slide axially in the member 50. The door sheet 44, when in released position, assumes a semi-cylindrical shape with the axis of the cylinder parallel to the door support 56 so that a vertical projection of the door is in the form of an ellipse with a major axis greater than the diameter of opening 30 and a vertical minor axis less than that diameter. By swinging the door strap 56 about its pivot 58, the door can be moved through the opening 30. The play between the neck 52 and opening 54 makes it possible to manipulate handle 64 on rod 48 in such manner as to move the door somewhat relative to its supporting strap 56 and thus facilitate movement of the door through opening 30. When the door is in the position shown in Fig. 4, it can be brought into engagement with the sealing ring 66 at the inner side of the opening 30 by pulling outward on the center of the door. I shall now describe more fully the manner and means by which this is accomplished.

Referring more particularly to Figs. 2, 4 and 5, it will be seen that the sleeve 50 has an inclined or cam shaped outer end 68 and that the handle 64 has a sleeve-like extension 70 provided with a complementary inclined surface 72 which engages the inclined surface 68. The handle and its sleeve 70 are freely rotatable on rod 48 and are retained in place by a C spring 74 engaging in complementary grooves in the sleeve 70 and rod 48 adjacent the outer end of this rod. Rotation of handle 64 rotates sleeve 70 and causes it to shift from the position shown in Fig. 4 to that shown in Fig. 2 and this shift in position moves the rod 48 outwardly and brings the door 32 into sealing engagement with sealing ring 66.

When it is desired to open the door, the handle 64 is rotated through 180° to move its sleeve 70 from the position shown in Fig. 2 to that shown in Fig. 4 and thereafter the door can be withdrawn by swinging this door and its supporting strap 56 about pivot 58. In carrying out this withdrawing operation, the movement of the door through opening 30 may be further facilitated by manipulating handle 64 to pivot the door somewhat in its supporting opening in the strap 56 so that the left hand end of the door, as viewed in Fig. 4, will pass to the right of the left hand wall of the door opening.

The base of the container 20 is adapted to be filled with water to approximately the height indicated in Fig. 1 and a pair of electrical heating elements 76 and 78 (Figs. 1 and 12) are immersed therein. The heating elements 76 and 78 are connected to a three-pronged plug 80, secured in a wall of the container 20 and adapted to be connected by a three-wire conduit to the control mechanism located in a control box 82 containing the switch mechanism and timing means for energizing and deenergizing the heating elements 76 and 78.

One end of the box 82 is provided with a dial 84 graduated in minutes and having a stop pin 86. A control handle 88 normally has its long end 90 in contact with the stop pin 86. The control handle 88 is attached to one end of a shaft 92 extending lengthwise of the control box 82 and passing through a conventional spring motor drive and escapement mechanism indicated generally at 94 and hereinafter referred to as clockwork mechanism.

A pair of mercury switches 96 and 98 are mounted in spring clips 100 and 102, freely pivoted on the shaft 92 and control the circuits leading to the heating elements 76 and 78. The switch 96 is so positioned that its own weight tends to swing it about the shaft to cause it to assume the vertical closed position shown in Fig. 10 and this switch is moved to open position by an arm 104 which is affixed to shaft 92 in non-rotatable relationship thereto by screw 106. The arm 104 for certain positions of the shaft 92 engages a laterally projecting finger 108 integral with switch supporting clip 100.

The switch 98 is moved to and from closed position by a U-shaped frame 110 having arms 112 and 114 resting beneath opposite ends of the mercury switch 98. As best shown in Fig. 10, the frame 110 is composed of members 116 and 118, lying on opposite sides of the shaft 92, a felt friction strip 120 being interposed between the shaft and members 116 and 118. Any desired frictional engagement between the frame 110 and the shaft 92 can be secured by rotation of screw 122 to increase or decrease the friction between this frame and the shaft. The screw 122 is threaded into the lower frame member 110 and a spring 124 presses the upper frame member 118 toward the lower frame member 110 with varying degrees of pressure, depending upon the adjustment of the screw 122.

I have provided means for limiting the movement of the switch 98 with the shaft 92. This means comprises a U-shaped stop member 126 which is riveted or otherwise suitably secured to one wall of the box 82 and has inwardly projecting ends 128 and 130 alternately engaged by the adjacent portion of the switch supporting frame 110. The arms 128 and 130 are preferably spaced so that the time consumed by the clockwork mechanism in moving the frame 110 from engagement with the arm 130 into engagement with the arm 128 corresponds to the length of time required to bring the water in the container 20 to boiling temperature and raising the steam pressure for sterilizing to a predetermined pressure, e. g., 15 lbs. gauge, which represents a sterilization temperature of 250° F.

The clockwork mechanism 94 is provided with a bell 132 which is rung by a hammer, not shown, when the articles placed in the container 20 have been completely sterilized. In lieu of the bell 132, any other suitable visible or audible indicator could be used.

The electrical connections are indicated in the diagrammatic view of Fig. 12. In this view, the wires 142 and 144 lead from the switch box 82 and are connected with the house lighting system or other source of supply and in the actual device would take the form of a conventional, flexible, insulated, electric cord having a plug to be inserted in an ordinary wall socket. The high resistance, low output heating element 76 is connected in series with its control switch 96 in a circuit 146 which is connected across the wires 142 and 144 and also connected across these wires in a second parallel circuit 148 containing the low resistance, high output heating element 78 and its control switch 98 arranged in series.

While the control mechanism which I have just described makes it very unlikely that any excessive steam pressure will ever be built up in the container 20, I prefer to provide appropriate safety means so that even the most abusive use of my sterilizer can not produce an explosion. I have, therefore, provided the upper wall of the container 20 with a nipple 134 having an open upper end which is closed during sterilization by a weight 136 resting thereon. This weight constitutes a safety valve and if the pressure in the container 20 rises above normal, the weight 136 will lift sufficiently to relieve this pressure and will thereafter re-seal with the upper end of the nipple 134 to prevent further escape of the steam from the container 20.

A conventional pressure gauge 138 is illustrated as being attached to a side outlet in the nipple 134 to indicate at all times the pressure existing in the container 20. As a further safety measure, I have also provided the upper wall of the container with a blow out plug 140 of synthetic rubber or other suitable material and this plug will blow out before the pressure in the container reaches a sufficiently high value to destroy the container.

In order to condition my sterilizer for use, the wires 142 and 144 are connected to a suitable source of electrical energy and the bottom of the container 20 is filled with water to approximately the level shown in Fig. 1. The articles to be sterilized are then placed upon the shelves 34, 36, and 38 and the door 32 is swung into a position shown in Fig. 4. Handle 64 is rotated through 180° to pull the door into sealing engagement with sealing ring 66, as shown in Fig. 2.

In a particular embodiment, the high output heating element 76 had a capacity of 1000 watts and the low output heating element 78 had a capacity of 250 watts. Two and one-half minutes were required to bring the water in the container 20 to boiling temperature and to create the desired steam pressure in this container. After this pressure had once been created, the 250 watt heating element was adequate to maintain this pressure and after both heating elements had been turned off, the pressure in the container dropped to atmospheric pressure in about four minutes.

If the operator using this particular embodiment of my invention turned the control handle 88 until the long end 90 pointed at 15, the shaft 92 would be rotated in a clockwise direction through 180° and this movement would correspond to a sterilizing or operating period of fifteen minutes. The first part of this clockwise movement of the shaft 92 would close the switch 98 and energize the high output heating element 78 and when the shaft 92 and switch 98 had

75 moved through an arc corresponding to 2½ minutes on the dial 84, further clockwise movement of the switch 98 would be arrested by engagement of the left hand end of the switch supporting frame 110 with the stop finger 130.

When the shaft 92 had been rotated in a clockwise direction through a distance corresponding to four minutes on the dial 84, switch 96 would close, thereby energizing the low output heater 10 76. Switch 96 would continue to move with the shaft 92 until the heavy end of this switch reached its lowermost position, whereupon further movement of the switch 96 would cease and further movement of the shaft would merely cause separation of switch finger 108 and control arm 104. This clockwise rotation of the shaft 92 by the operator winds up the clockwork mechanism 94 and as soon as the operator releases the control handle 98, this clockwork mechanism starts to 15 rotate shaft 92 and handle 88 in a counter-clockwise direction.

20 The energization of heating elements 76 and 78 raises the temperature of the water in the base of the container 20 until steam is given off 25 and until the pressure of this steam reaches the desired maximum. In the particular heater selected for purposes of illustration only, this requires 2½ minutes and takes place while the shaft 92 is being moved counter-clockwise through 30 an angle corresponding to 2½ minutes on the dial 84. This counterclockwise movement of the shaft moves switch 98 in a counterclockwise direction and the circuit through this switch is broken just before the switch supporting frame 35 110 engages the stop 128. Further movement of the shaft 92 in a counterclockwise direction merely produces slippage between this shaft and the felt 120 clamped in the frame 110.

30 After the high output heating element 78 has 40 been cut out, the low output heating element 76 continues to supply heat to the water in container 20 and to maintain the desired steam pressure therein. The heating element 76 is designed to produce slightly more heat than is necessary 45 to maintain the desired steam pressure and excess steam escapes by slightly lifting the weight 136 which in normal operation maintains a constant maximum pressure in the container 20. The pressure existing in the container 20 is indicated 50 at all times by the gauge 138.

As the shaft 92 continues to rotate in a counter-clockwise direction, arm 104 engages switch finger 108 and causes switch 96 to move with shaft 92. After the shaft has moved through an arc corresponding to 11 minutes on the dial 84, switch 96 55 opens and breaks the circuit of the heating element 76.

Thereafter, no further heat is supplied to the water in the container 20. The pressure in the 60 container drops to atmospheric pressure in about four minutes, at which time, the end 90 of control handle 88 will have engaged stop 86 and shaft 92 comes to rest. Just as this occurs, the bell 132 rings and gives an audible notice that 65 the sterilizing operation has been completed. Thereupon the operator removes the weight 136 to make certain that the pressure has dropped to atmospheric, and then opens the door 32 by first rotating handle 64 through 180° and then swinging the door about pivot 58. The articles placed upon the shelves can be removed.

70 Since the weight 136 rests freely upon the upper end of the nipple 134, there is no danger that this type of safety valve will stick. The only circumstances under which a further safety

control would be useful, is where a heavy towel or other article is carelessly thrown or placed over the weight 136. Under these circumstances the plug 140 would blow out before the pressure in the container 20 could rise high enough to burst this container.

It will be understood by those skilled in the art that the particular values referred to in describing the operation of a particular embodiment of my invention were illustrative only and that the heating elements may be given any other values desired. The time required to raise the temperature in the container to operating temperature will, of course, vary with the output of the heating elements, the volume of water in the container, and various other factors. An important feature of my invention, however, resides in the arrangement whereby the maximum heating current is required only during the initial operation of the sterilizer and thereafter only a minimum heating current is required. Even this minimum current is cut off an appreciable time before the sterilizing operation is completed, in order to utilize the heat stored up in the water and in the container itself. This feature materially increases the efficiency of operation and reduces the current consumption.

The embodiment of Figs. 13 and 14 differs from the previous embodiment and principally in the means for mounting the flexible door. In this embodiment, the container 200 is mounted in a pair of annular supporting members 202, of which only one is shown. It will be understood that these supporting members may be provided with suitable legs generally similar to those shown in the previous embodiment. The annular support shown in the drawing is provided with a pair of ears 204 to which a hinge 206 is pivotally connected by one leg of a U-shaped hinge pin 208. The other leg of this hinge pin forms a pivotal connection between the hinge 206 and one end of a door supporting strap 210.

The flexible door 212 is substantially identical with the door 32 of the previous embodiment. This door has a central rectangular opening receiving the square section 214 of a mounting screw 216. The leaf spring 218 has a similar squared opening and is clamped between the door 212 and shoulder 220 of the mounting screw 216. The door and spring are secured to the mounting screw by a nut 222 threadedly engaging an extension 224 of the mounting screw. A washer 226 is preferably interposed between the nut 222 and the door 212 to make a steam-tight joint.

The mounting screw 216 is supported in a sleeve 228 rotatable in the cylindrical recess 230 formed in a boss 232 which constitutes an integral part of the door supporting strap 210. The sleeve 228 is provided with a threaded portion 234 which engages the main threaded portion of the door mounting screw 216. The anti-friction washer 236 may be interposed between an end of the sleeve 228 and a flange 238 which limits inward movement of this sleeve.

The sleeve 228 is rotated by a knob or handle 240 made of Bakelite or other suitable material and having a metal thimble 242 moulded therein. The thimble 242 has a cylindrical recess which freely receives the outward end of the mounting screw 216 so that this end of the mounting screw moves in and out of this cylindrical recess as the handle 240 and sleeve 228 are rotated. A screw 244 serves to attach the sleeve 228 to the tubular extension 246 of the knob 240, but

torque is transmitted from the knob to the sleeve through means described below.

The outward end of the mounting screw 216 has a tap recess into which is screwed a screw 248 having a head whose diameter is approximately the diameter of the apexes of the threads on the mounting screw. The head of screw 248 thus prevents sleeve 228 from being entirely removed from the mounting screw 216 in the normal operation of the mechanism.

In Fig. 13 the door is shown in full lines in the closed position. In this position the turned over edge 250 of the flexible door 212 is in sealing engagement with the sealing ring 252 carried by the container 200, and the free end 254 of the door supporting strap 210 is firmly engaged against the end of the container 200. When it is desired to open the door, the knob 240 is rotated in a counterclockwise direction. This permits the mounting screw 216 to move inwardly under the influence of spring 218 and as rotation of knob 240 continues, the flexible door 212 assumes a semi-cylindrical shape with the axis of the cylinder parallel to the door supporting strap 210. Rotation of the knob 240 is limited by engagement of the threaded part 234 of the sleeve 228 with the head of screw 248 and when this occurs the door is in the completely collapsed position.

It is to be noted that the outer end of sleeve 228 is provided with notches 256 which receive ribs 258 of knob 240 and that these ribs serve to transmit to the sleeve 228 the rotative force exerted on the knob 240.

When the flexible door has been sufficiently collapsed, the knob 240 is moved to the right to cause the parts to assume the dotted line positions shown in Fig. 13. Thereafter the door can be swung out of the container by merely pulling on the knob 240. When it is desired again to seal the container, the door is swung back into the open end of the container. As the door enters the container, the knob 240 is moved to the right to place the righthand part of door edge 250 behind the adjacent part of the sealing ring 252 and just before the free end 254 of the door supporting strap engages the end of the container, the knob 240 is moved to the left to centralize it relative to the container and to bring the lefthand portion of the door edge 250 behind the lefthand portion of the sealing ring 252.

Knob 240 is now rotated in a clockwise direction and this draws the mounting screw 216 and the central portion of the door outwardly, or downwardly, as viewed in Fig. 13. The door thereupon assumes a generally circular shape and the entire edge portion 250 contacts the sealing ring 252 and forms a fluid-tight seal therewith. Rotation of the door and mounting screw 216 is prevented by the leaf spring 218, which has a rectangular opening engaging the rectangular portion 214 of the mounting screw and which has ends 260 and 262 slidably engaged in longitudinal grooves 264 and 266 formed in the door supporting strap 210.

In the embodiment of Figs. 13 and 14, I have also shown a different arrangement for the pressure gage and pressure release valve. In this embodiment the pressure gage 268 is arranged in an inclined position so that it is more easily read. The pressure release valve is provided with a pivoted bail 270 which, in the position shown, overlies the weight 272 and prevents it from being blown off of its supporting nipple. The upper

end of the wire bail 270 may be swung to one side to permit removal of the weight 272 if desired. Except as hereinabove described, the embodiment of Figs. 13 and 14 may be identical with the previous embodiment and further description of the embodiment of Figs. 13 and 14 is, therefore, unnecessary.

It is to be understood that my invention is not limited to the details herein shown and described, but may assume numerous other forms and that my invention is to be construed as including all variations and modifications falling within the scope of the appended claims.

I claim:

1. In a sterilizer of the class described, the combination of a container having an opening through which articles to be sterilized may be inserted and may subsequently be withdrawn, a sealing ring on the inside of said opening, a door formed of flexible material and biased toward a curved position permitting said door to be passed through said opening, a pivotal support having an elongated slot therein, a door supporting member engageable in said slot for supporting the door from said pivotal support, said member being shiftable longitudinally of the slot to facilitate manipulation of said door for passing the same through said opening, a handle, including cam means, for flexing said door into sealing position, and means for creating steam pressure in said container to sterilize articles placed therein, said door in closed position serving to prevent escape of steam from said container and being sealed more tightly by increased pressure in said container.

2. In a device of the class described, the combination of a container having an opening therein and a sealing surface on the inside of said opening, a door of suitable size for making a fluid-tight seal with said sealing surface, said door being normally curled to a shape permitting it to pass through said opening, a support for said door hinged at one end to said container adjacent said opening, said support having a free end adapted to engage the edge of said opening diametrically opposite the hinged connection between said support and container, a handle for moving said door through said opening, and cam means carried by said handle for deforming said door into sealing engagement with said sealing surface.

3. Apparatus of the class described comprising a container having a cylindrical opening surrounded by an internal sealing surface, a door including a flexible plate normally curled to form a portion of the wall of a cylinder but capable of being deformed into a dish shape and when so deformed having a maximum diameter greater than the diameter of said opening, a support for said door, a hinge for said support, said hinge being located at one side of said container, the unhinged end of said support being adapted to engage the opposite wall of said container when

said door is in sealing position, said support having a rectangular opening therein, a member having a rectangular neck loosely fitting in said opening, a door supporting rod slidable in said member, cam means for sliding said rod axially in said member, and a handle for actuating said cam means and for moving said door through said opening.

4. Apparatus of the class described comprising a container having an opening, a door for sealing on the inner side of said opening, a supporting strap for said door, said door having a dimension in the plane of said strap greater than the corresponding dimension of said opening, a hinge, a pivotal connection between said hinge and strap, and a second pivotal connection between said hinge and container to permit lateral shifting of said door in the direction of said dimension.

5. Apparatus of the class described comprising a container having a circular opening, a door sealing on the inner side of said opening and flexing to permit said door to be moved through said opening, a mounting stud attached to said door, a supporting strap for said door, a hinge connecting said strap to said container, said strap having a cylindrical recess, a sleeve rotatable in said recess and threadedly engaging said mounting screw, a handle for rotating said sleeve, a spring confined between said door and strap and preventing rotation of said door and mounting screw relative to said strap, and means preventing separation of said sleeve and mounting screw.

6. Apparatus of the class described comprising a support, a supporting strap, a hinge connecting the strap to said support, a door mounted on said supporting strap and having a dimension in a direction parallel to said strap which is greater than the corresponding dimension of an opening through which said door is adapted to pass, and means for guiding the door for limited movement relative to the strap in a direction longitudinally of the strap.
